George V. Hazard

UNITED STATES PATENT OFFICE.

GEORGE V. HAZARD, OF TORREY, NEW YORK.

DOOR-FASTENER.

Specification of Letters Patent No. 26,494, dated December 20, 1859.

To all whom it may concern:

Be it known that I, GEORGE V. HAZARD, of Torrey, in the county of Yates and State of New York, have invented a new and Improved Door-Fastener; and I do hereby declare that the following is a full and exact description thereof, reference being had to the accompanying drawings and to the letters of reference marked thereon.

10 A is a metallic plate tapering from near its middle on one or both edges to each end and bent so that the sides are parallel and of equal length and at a proper distance from each other, according to the size of fastener intended. In each side is a slot extending from near the points of A, about half the length of each side, in such direction that the parts of A between the slots and the door or door casing shall be wedge shaped

15 for the purpose of pressing and holding the door close to its casings.

B is a metallic hooked or toothed bar of suitable size and strength at the end opposite to the hook, and on the same side with it are two ears c' c', turned up from the edges or attached, or the end of B may be bent around, forming a hole through which

and the slots in the sides of A the pivot C passes, holding B in place and movable in and traversing the slots. B is made to fit 30 and shut compactly and securely into A when the pivot is nearest the points of A, covering the hooks or teeth and inclosing them as in a box.

To apply this fastener to a door, draw 35 the pivot to the points of A, place the hook or teeth of B against the rabbet of the door and the bar across it, the part A being held in a direct line with B, or nearly so, or inclined from the door, then shut the door 40 upon the bar, driving the hook or teeth into the jamb, turn down A upon the door or casing and crowd it along upon the pivot, thereby forming a catch resting close against the door and casing and held by the bar B. 45

What I claim as my invention and desire to secure by Letters Patent is—

The part A constructed and arranged as and for the purposes set forth.

GEO. V. HAZARD.
